COMBINED PORTABLE PROJECTOR AND FOLDING SCREEN

Carlos J. Cardona, North Hollywood, Calif., assignor to
Cardona Company, Inc., North Hollywood, Calif., a
corporation of California

Filed Aug. 13, 1963, Ser. No. 76,200

Term of patent 14 years

(Cl. D61—1)

FIG. 1.

FIG. 2.

FIG. 3.

FIG. 4.

FIG. 5.

FIG. 1 is a side elevational view of a combined portable projector and folding screen showing my new design;

FIG. 2 is a top plan view of FIG. 1;

FIG. 3 is an elevational view of the side opposite that in FIG. 1;

FIG. 4 is a front elevational view thereof; and

FIG. 5 is a rear elevational view thereof.

I claim:

The ornamental design for a combined portable projector and folding screen, as shown.
